(57) **CLAIM**

I claim the ornamental design for a skate wheel jar, as shown and described.

DESCRIPTION

FIG. 1 is a perspective view of a first embodiment of a skate wheel jar, depicting my new design;

FIG. 2 is a side elevational view thereof, wherein the side is cylindrical and has the same ornamental features about the device;

FIG. 3 is a perspective view thereof, wherein the lid is removed from the base;

FIG. 4 is a perspective view of a second embodiment of the skate wheel jar, depicting graphics displayed on the top;

FIG. 5 is a front side elevational view thereof, the rear side being a mirror image;

FIG. 6 is a right side elevational view thereof, the left side being a mirror image; and,

FIG. 7 is a perspective view thereof, wherein the lid is removed from the base.

The broken lines shown in the Figures are for illustrative purposes only, and form no part of the claimed design.
